UNITED STATES PATENT OFFICE

WALTER C. ASTRUP, OF CLEVELAND, OHIO, ASSIGNOR TO THE ASTRUP COMPANY, OF CLEVELAND, OHIO, A CORPORATION OF OHIO

AWNING BRACKET

Application filed October 4, 1930. Serial No. 486,413.

The invention relates to awnings, and more particularly to an awning bracket or combined head rod and rafter bar holder for stationary awnings.

Present types of stationary awnings which usually include a frame, supporting preferably fabric awning material, are provided with rafter bars slidably mounted by slip-T's at one end on one of the longitudinal frame members and by eye ends on the other end on another longitudinal frame member. The rafter bars strengthen the frame and provide supports for the fabric awning material.

These stationary awnings are erected in a fixed, usually sloping position by attaching eye screws or bolts to the side wall of the structure from which the awning projects, by stringing the upper longitudinal frame bar, usually called the head rod, through the screw eyes for supporting the same therefrom, by providing strut rods attached at one end to the structure and at the other end to the outward corners of the frame for maintaining the same in sloping position, and by tying the awning fabric to the head rod at a large number of places.

However, the eye screws or bolts do not hold the head rod from side slipping so that the awning chatters and rattles during wind storms, and because of looseness from vibration, the eye screws or bolts must be replaced approximately every two years.

Thus, a constantly increasing number of holes, wherein screw eyes or bolts were once located are made in the side wall of the structure, by the recurring replacement of the eyes or bolts, which holes mar the appearance of the structure side wall, and ultimately weaken the condition of the structure side wall eye screw or bolt attaching portion.

Moreover, the slip-T and eye end connections of the rafter bars on the frame permit a shifting of the rafter bars longitudinally of the frame which spoils the even spacing and fabric supporting function of the rafter bars and causes rattling of the rafter bars during wind storms.

And finally, much time and labor is re-

quired for tying the upper edge of the awning fabric to the head rod, each time that the awning is erected.

Accordingly, one of the objects of the present improvements is to provide rigid supports, clamps or brackets for a stationary awning head rod which will prevent side slipping and rattling of the frame and from which the head rod may be detached without detaching the brackets from the structure wall, thus eliminating any marring or weakening of the structure wall by the recurring erection and dismantling of the awning to the structure wall bracket attaching portion.

A further object of the present improvements is to provide rigid supports or brackets for the awning rafter bars which will prevent shifting and rattling of the rafter bars.

A further object of the present improvements is to provide a stationary awning construction in which the head rod may be slipped into a hem formed in an edge of the awning fabric, so as to avoid tying the fabric to the head rod.

And finally it is an object of the present improvements to provide combined head rod and rafter bar holders or brackets for stationary awnings, with which the head rod and rafter bars may be quickly attached or detached for readily, quickly and easily erecting or dismantling stationary awnings.

These and other objects may be attained by providing an awning bracket construction, preferred embodiments of which are herein-after described in detail and shown in the drawings, which may be stated in general terms as including a base member adapted to be attached to a structure wall, a movable member associated with the base member, the base member and movable member being provided with cooperating clamping portions adapted to receive a head rod to be clamped, means for effecting a clamping action between said cooperating clamping portions, and means on one of said members for detachably supporting a rafter bar closely adjacent the head rod.

In the accompanying drawings:

Figure 1 is a perspective view of a stationary awning in which the awning head rod and rafter bars are supported by a plurality of improved awning brackets;

5 Figure 2 is a vertical cross-section taken on the line 2—2, Figure 1;

Figure 3 is an enlarged side elevation of the bracket shown in Figure 1, mounted on a concrete or brick structure wall;

10 Figure 4 is a front elevation of the bracket shown in Figure 3, the rafter rod eye end being shown in section;

Figure 5 is a vertical section taken on the line 5—5, Figure 4;

15 Figure 6 is a front elevation similar to Figure 4, showing a modified form of improved bracket adapted for being mounted on a wooden structure wall; and

Figure 7 is a vertical section taken on the line 7—7, Figure 6.

Similar numerals refer to similar parts throughout the several figures of the drawings.

20 The sloping stationary awning generally indicated at 10, and shown in Figure 1, includes the frame consisting of a head rod 11, and a lower longitudinal rod 13.

25 The frame carries the fabric awning material 15, and is supported by the strut rods 16, mounted at 17 on the structure wall 18, and provided with elbows 19, mounted on the rod 13. These strut rods determine the location of the outer edge of the awning frame with reference to the wall 18, while the upper 30 or inner edge of the awning is supported by the improved brackets generally indicated at 20 mounted on the structure wall 18.

35 The awning also includes frame strengthening and fabric material supporting rafter bars 21, provided at one of their ends with 40 slip-T's 22 mounted on the rod 13, and the bars 21 are mounted at their other ends on the brackets 20.

45 Each bracket 20 includes a base member 23 and a movable member 24, and each bracket 20 is mounted on the stone, concrete or brick wall 18, by a lag bolt 25 which passes through the aperture 26 formed in the base member 23. The preferably squared head 27, of the 50 lag bolt 25, is received in the squared recess 28 formed in the front face of the base member 23 communicating with the aperture 26, and prevents the base member from turning when mounted on the wall 18.

55 A bolt 29 and a wing nut 30 are utilized for connecting the base member 23 and movable member 24 together in clamping relation. The base member 23 and movable member 24 are provided with cooperating 60 concaved clamping portions 31 and 32, respectively, which receive and clamp the head rod 11 and the hem of the fabric 15 surrounding the same, when the members 23 and 65 24 are drawn together in clamping relation by the bolt 29 and nut 30.

The base member 23 is also provided with ears 33, projecting outwardly therefrom adjacent and below the clamping portion 31, and the ears 33 mount a nut and bolt 34, on which is journaled the eye end 35 secured to the upper end of the rafter bar 21.

70 In erecting the stationary awning 10, the required number of brackets 20 are mounted on the structure wall 18 at the desired positions, and the awning head rod 11 is slipped into the hem of the fabric material 15 and mounted by the brackets 20 simply by clamping the head rod 11 between the base and movable members 23 and 24 of the several brackets 20. The rafter bar eye ends 35 are secured by the bolts 34 on each bracket 30. The strut rods 16 and lower rod 13 with the rafter bar slip-T's 22 mounted thereon are then erected by mounting the strut rods at 75 17 on the wall 18. The fabric material is then tied to the lower rod 13 and the erection of the awning 10 is complete.

80 The brackets 20 clamp the awning 10, and mount the rafter bars 21 against vibration and rattling, securely and rigidly on the structure wall 18 at the required fixed position. Moreover the awning may be dismantled very quickly and easily, without marring the structure wall surface, simply by loosening the nuts 30 and swinging the movable members 24 to the position shown in 85 dot-dash lines in Figure 4 of the drawings, whereupon the head rod 11 may be removed from the bracket 20.

90 The awning fabric hem is then slipped off of the head rod 11, the ties between the fabric and lower rod 13 are severed, and the awning fabric may be stored for any desired time.

95 It may also be desired to dismantle the frame, whereupon the bolts 34 are then removed for disconnecting the rafter bars from the brackets, and the strut rod mountings 17 are disconnected, so that the frame may be packed for storage, to be again quickly erected at any desired future time.

100 The modified form of bracket 20a shown in Figures 6 and 7 is adapted for being mounted on a wooden structure wall 18a by wood screws 25a, secured in the apertures 26a. Otherwise the structure and use of the 105 brackets 20a is the same as that of the brackets 20.

110 I claim:

1. An awning bracket including a base member adapted to be attached to a structure wall, a movable member associated with the base member, the base member and movable member being provided with clamping portions adapted to receive and clamp an awning head rod, means for effecting a 115 clamping action between said clamping portions, and means on one of said members adapted for detachably supporting an end of an awning rafter bar closely adjacent the head rod.

120

125

130

2. An awning bracket including a base member adapted to be attached to a structure wall, a movable member associated with the base member, the base member and movable member being provided with cooperating concaved portions for receiving and clamping an awning head rod, means for effecting a clamping action between said cooperating concaved portions, and means adapted for detachably supporting an end of an awning rafter bar including ears on the base member and a bolt removably carried by the ears.

3. In combination with an awning frame having a head rod and a rafter bar, a head rod and rafter bar bracket, means on the bracket for removably clamping the head rod in a fixed position, and means on the bracket for detachably mounting one end of the rafter bar closely adjacent the clamping means.

20 In testimony that I claim the above, I have hereunto subscribed my name.

WALTER C. ASTRUP.
